ABRASIVE DEVICE

Frans O. Albertson, Sioux City, Iowa, assignor to
 Albertson & Company, Inc., Sioux City, Iowa,
 a corporation of Iowa

Application May 9, 1938, Serial No. 206,738

4 Claims. (Cl. 51—197)

The present invention relates to abrasive devices, and is particularly concerned with devices adapted to be used for finishing and smoothing operations, such as a pad or support for holding a rotating sanding disc.

The present invention is an improvement over that covered by the prior Patent No. 1,882,693, issued October 18, 1932, to F. O. Albertson and Gustav A. Olsen for an Abrasive device.

10 While the present abrasive device is adapted to be used at any speed, it is particularly adapted to be used at relatively high rotating speeds, and for this purpose all of its parts are made as light and strong as possible.

15 In the use of rotating abrasive discs it is found that only a portion of the disc adjacent the periphery becomes used up or filled with gummy adhesive materials, such as paint, and it has become customary to trim off the periphery of a 20 relatively large abrasive disc and then apply it to a smaller supporting pad for further use. Such trimming operations may, for example, be carried out by means of an apparatus of the type shown in Patent No. 2,066,381, issued January 5, 1937.

25 In order to use up fully such an abrasive disc according to the methods of the prior art, it has been necessary to provide a multiplicity of supporting pads of different sizes, such as, for example, a 9 inch, 7 inch, 5 inch, and even a 3

30 inch pad has been used. This involves considerable expense, since it is necessary to provide a plurality of separate pads of different sizes, and the devices of the prior art have been heavier than is found necessary in the specific construction which forms the subject of the present application.

35 One of the objects of the invention is the provision of an improved abrasive disc support which is adapted to be used with abrasive discs of various different sizes whereby one supporting device 40 may perform the functions of a plurality of devices which were used in the prior art.

Another object of the invention is the provision of an improved support for abrasive discs 45 which is adapted to flex at its periphery when sufficient pressure is applied to it so that the abrasive disc is resiliently forced against the work to which it is applied.

Another object of the invention is the provision 50 of an improved abrasive device which has no metal parts, so disposed as to be likely to engage the surfaces which are being polished.

Another object is the provision of an improved 55 abrasive disc supporting member having means for securing the abrasive disc to a driving shaft

which is so constructed that it may be quickly attached and quickly detached and also so constructed that it will not become so tightly wedged or screwed on the shaft that difficulty will be encountered in its release.

5 Another object is the provision of an improved backing disc which is adapted to give fuller surface contact when the sander is tilted and by means of which clogging of the abrasive is eliminated.

10 Another object of the invention is the provision of an abrasive disc-supporting device which is light, sturdy, capable of economical manufacture, and adapted to be used for a long period of time without necessity for any replacement or 15 repair of its parts.

20 Other objects and advantages of the invention will be apparent from the following description and the accompanying drawings, in which similar characters of reference indicate similar parts throughout the several views.

25 Referring to the two sheets of drawings accompanying this specification,

Fig. 1 is a side elevational view of a sanding machine used for driving an abrasive device constructed according to the present invention;

Fig. 2 is a front plan view of the abrasive device, partially broken away to show internal structure;

Fig. 3 is a sectional view, taken on the plane 30 of the line which passes through the axis of the drive shaft of the device, with a relatively small abrasive disc applied to the support;

Fig. 4 is a view similar to Fig. 3, with the largest form of abrasive disc applied to its support; 35

Fig. 5 is a view similar to Figs. 3 and 4, with an intermediate size of abrasive disc applied to the support;

Fig. 6 is a sectional view taken on the plane 40 of the line 6—6 of Fig. 5, looking in the direction of the arrows;

Fig. 7 is a sectional view, similar to Fig. 5 of the preferred form of the invention, having an improved construction of backing disc;

Fig. 8 is a similar view of a modification employing a smaller form of the same improved backing disc, for the purpose of utilizing smaller abrasive discs. 45

Referring to Fig. 1, the sanding machine is indicated in its entirety by the numeral 10. It is 50 provided with a drive shaft 11 (Fig. 3) having an enlargement 12 adapted to be engaged by a peg 13 carried by a pivotally mounted arm 14 for securing the drive shaft in fixed position when attaching the abrasive supporting pad. 55

The abrasive supporting pad is indicated in its entirety by the numeral 15, and it supports a sheet of abrasive 16. The drive shaft 11 has an annular shoulder 17 between the enlargement 12 and the reduced cylindrical portion 18, and it is provided with a still further reduced threaded end 19 for receiving a threaded member 20.

The threaded member 20 comprises a hardened metal member of regular polygonal form in cross section, as shown in Fig. 6, and I prefer to make the external shape or surface of the threaded member 20 hexagonal, the hexagonal exterior being indicated by the numeral 21 (Fig. 6).

The member 20 is provided with the internal bore 22, which has threads complementary to the reduced threaded end 19. The length of the reduced threaded portion 19 is such that the annular shoulder 23 never interferes with the threaded member 20 because the threaded portion 19 is 20 amply long for its purpose.

The threaded member 20 is provided with a head 24, which is circular, as shown in Fig. 2, and which tapers gradually toward the outer edge 25. As the rear side 26 of the head 24 is flat or plane, 25 the front side 27 is, therefore, slightly convex. The head 24 is adapted to be drawn in substantially flush with the outer surface of the abrasive disc 16, due to the shape of the abrasive disc and the shape and structure of the supporting 30 pad 15.

The supporting pad 15 is provided with a hub 28, which is preferably formed of light sheet metal, such as an aluminum alloy, and it may be constructed of a pair of cup shaped members 35 29 and 30. The cup shaped member 29 has a flat circular body 31, which is provided with a centrally located circular aperture 32 for receiving the reduced cylindrical portion 18 of the drive shaft. It has a cylindrical body flange 33, which 40 extends forward, and a radially extending attaching flange 34, which is provided with apertures 35 for receiving rivets 36.

The cup shaped member 30 likewise has a flat circular body 37 provided with a hexagonal aperture 38 for receiving the threaded member 20. 45 It also has a cylindrical body 39 and a radially extending attaching flange 40 provided with apertures for receiving rivets 36.

The two cup shaped members 29 and 30 are 50 preferably fixedly secured together by rivets 36, and the same rivets may support a radially extending metal disc 41, which may be also constructed of an aluminum alloy.

The disc 41 has a centrally located aperture 55 42 for passing the cylindrical body 39 of the cup shaped member 30. It also has the registering apertures for the rivets 36, and it may be provided with an offset at 43 for causing the outer portion of the disc 41 to project forward slightly. 60 The apertures 44 are for the purpose of permitting the portions of the molded rubber disc 45 to extend in the threaded apertures 44 to anchor the rubber to the metal disc 41. The rubber pinion 45 is preferably made of relatively hard, 65 molded rubber, which is cast in place, and which is characterized by its hardness and resilience to flexure, rather than by its softness.

The rubber disc 45 is intended to flex, but need 70 not necessarily have any cushioning effect due to the compression of its parts on the face 46 of the disc. The rubber disc 45 is cast about the metal disc 41, and it is provided with a plurality of layers of fabric 47, tending to reinforce the rubber disc. Its shape may be circular in plan, and in cross section it may taper, as at 48, to make

the disc thinner at the edge 48, and the front face is provided with a plane surface 46. The thickness of the rubber disc 45 is such that the plane surface 46 projects farther outward than the plane surface 50 on the end of the body flange 37 of the cup shaped member 30. Thus the abrasive disc 16 may be provided with a pre-formed, molded depression 51 for receiving the head 24 of the threaded member 20, or the depression 51 may be formed by the force applied to the head when the head is driven home to compress the abrasive disc 16 against the face 50 of the hub.

The abrasive disc 16 may consist of any desirable or suitable form of fiber, paper, fabric, or cardboard, provided with a facing of abrasive, 15 and having sufficient toughness to withstand the use to which such abrasive discs are put.

The supporting pad 15 shown in Fig. 3 is slightly smaller in size than five inches, as it is intended to support an abrasive disc of the five inch size.

The rubber disc 45 is provided with a cylindrical centrally located aperture 52, which is larger than the head 24 of the threaded member 20 so that the rubber disc will not interfere with the headed member. The face 46 of the rubber pad serves as a friction surface for engaging the rear side of the abrasive disc 16 and the face 50 of the hub for a similar purpose.

The central portion of the abrasive disc 16 is firmly clamped between the flat rear surface 26 of the head and the face of the hub 28, while the outer portion of the abrasive disc 16 has its rear surface drawn into closer frictional engagement with the front face 46 of the rubber pad 45 by virtue of the action of the headed member 20.

This is particularly so when the abrasive disc 16 is not provided with any pre-formed depression, but is adapted to be deformed by the action of the threaded member 20.

Referring to Fig. 5, this is another view similar to Fig. 3 of the same supporting pad and an abrasive disc which may be the same one as used in Figs. 1 and 3, before it has been trimmed down to the size of Fig. 3.

In this embodiment of the device, however, the threaded member 20 also supports a resilient fiber disc 53, which is clamped in place between the face of the rubber disc 45 and the abrasive disc 16. The fiber disc 53 is of a larger size than the rubber disc 45, as it is intended to be used to increase the size of the supporting pad. For example, the fiber disc 53 may be slightly less than seven inches in size, as it is intended to support the abrasive disc 16 when it is a seven inch disc.

The fiber disc 53 also has a centrally located aperture 54 for slidably engaging the hexagonal portion of the headed member 20, and it may have a centrally located pressed recess 55 of sufficient size to receive the head 24. In this case the threaded member 20 engages the abrasive disc and clamps it against the fiber disc 53, and clamps the fiber disc 53 against the rubber disc 45.

Referring to Fig. 4, in addition to the assembly of Fig. 5, in Fig. 4 I have employed an additional fiber disc 56, a larger fiber disc 53, and slightly smaller than the nine inch abrasive disc 16. This fiber disc 56 also has a hexagonal aperture 57 and a centrally located pressed recess 58 for receiving a head 24 of the threaded member 20. In this assembly the supporting discs 45, 53 and 56 gradually increase in size toward the outer edge of the supporting pad, and thus provide a supporting pad which is of the maximum resiliency 75

at its outer edge, but which is reinforced farther in by the discs 53 and 45.

The discs 53 and 56 are preferably constructed of a very tough, light and resilient fiber, which is known to the trade as Phenol Fiber, and which may be purchased on the open market, but for specific purposes the discs 53, 56 may be constructed of various types of light, resilient material. The material must also have a considerable tensile strength, as it is subjected to great strain by the centrifugal force which is developed by the rotation of the abrasive disc and supporting pad at speeds higher than have been used in the prior art, such as, for example, up to 4250

15 R. P. M.

The relation of strength to mass in discs 53, 56 is particularly greater than certain of the devices of the prior art, particularly those constructed of steel, so that the present devices may 20 be rotated at higher speeds.

The operation of my abrasive device is as follows:

The abrasive disc 16 may be bought in the nine inch size or may be cut out of sheets of abrasive and provided with the centrally located hexagonal aperture. In the first instance, the abrasive disc 16 is used with the assembly of Fig. 4, and after a period of use the abrasive surface of the disc 16 will become worn and probably filled with the results of abrasive action, but only adjacent the outer edge. By the use of a trimming machine, such as that exemplified in my prior patent, the outer edge to the extent of about one inch, for example, may be cut off, then 35 making the abrasive disc about seven inches in size.

Thereafter it may be applied to an assembly of the type shown in Fig. 5, and again used as a seven inch disc on the same supporting member. 40 When the next trimming has been made, the abrasive disc may be, for example, a pad five inches in diameter, and it may be directly applied to the supporting pad, as shown in Fig. 3. Thus one supporting pad is adapted to be used with 45 various different sizes of abrasive discs, performing the function of a number of the devices of the prior art, at a minimum cost.

Referring to Figs. 7 and 8, these are views which show the preferred mode of use of the invention 50 and the preferred form of backing disc. In this embodiment it will be noted that the supporting pad is of the same construction as that described in respect to Fig. 3.

The backing disc 70 is preferably constructed 55 of Phenol Fiber, a laminated, synthetic, resinous product which is adapted to resist exposure to moisture or high humidity. This product comprises laminations of fiber which are impregnated and bound together by a phenolic condensation 60 compound, and the fiber possesses the property of resisting warping or distortion when it is subjected to alternate wet and dry conditions.

The fiber also has a high physical strength so 65 that it can withstand rough usage, and it is relatively stiff, yet possesses sufficient flexibility to flex under pressure when the pad is applied at an angle to a working surface.

The backing disc 70 of Fig. 7 is slightly less than 70 nine inches in diameter and adapted to receive a nine inch abrasive disc 71. The backing disc 70 has its main body portion substantially in the same plane, but it is bent backwardly at the point 72 and provided with a frusto-conical border portion 73, the corner 74 of which is rounded off. 75 The backing disc has at its center a pressed de-

pression 75, which is adapted to receive the threaded member 24, and it may be secured to the pad in the same manner as the devices previously described. By means of the backwardly turned edge portion and rounded corner 74 a wider surface contact is secured between the abrasive disc and the work surface, and the clogging of the working surface of the abrasive by the paint is eliminated.

Referring to Fig. 8, this is a similar view, which 10 includes a backing disc 76 of the same construction, but of slightly smaller size, such as, for example, a disc slightly under seven inches in diameter, to receive the abrasive disc 71 when it has been trimmed down to the seven inch size. 15

In the preferred form of the invention only one 20 backing disc is mounted at any time, which increases the flexibility of the supporting pad over that of the pad when a plurality of backing discs are employed.

I desire it to be understood that the sizes 25 which have been set forth as examples herein are merely exemplary and need not necessarily be employed, as the supporting pad and reinforcing discs 53, 56 may be made in different sizes from that shown, or may be used in greater or lesser number.

It will thus be observed that I have invented an improved abrasive device which is adapted to be constructed more cheaply than the devices of 30 the prior art, and which is of a lighter construction, yet it is sufficiently strong to be rotated at higher speeds.

By means of the present equipment the abrasive 35 discs of large size may be used and trimmed down and operatively supported upon the same supporting device. The expense of the complete equipment has been materially reduced by my invention.

By means of the present improved backing disc 40 structure, clogging of the working surface of the abrasive by paint is eliminated, and a much wider contact area is secured in relation to the working surface.

The present supporting pads are lighter than 45 the devices of the prior art, due to the use of only one backing disc at any time in the preferred form of the invention, and they may therefore be rotated at higher speeds without damage.

While I have illustrated a preferred embodiment of my invention, many modifications may be made without departing from the spirit of the invention, and I do not wish to be limited to the precise details of construction set forth, but desire to avail myself of all changes within the 55 scope of the appended claims.

Having thus described my invention, what I claim as new and desire to secure by Letters Patent of the United States, is:

1. In a supporting device for an abrasive disc, 60 the combination of a hub comprising a hollow sheet metal member having a pair of apertures with a resilient, hard rubber disc carried thereby, and a plurality of additional resilient fiber discs of successively larger size adapted to be mounted 65 on said hub, and with an abrasive disc carried on the outside of the largest of said fiber discs, and means for securing all of said discs together to be driven by a common drive shaft, said abrasive disc being adapted to be trimmed at its 70 outer edge and applied to successively smaller discs by the omission of fiber discs larger than the abrasive discs, one of said apertures being a circular aperture, and the other of said apertures being a non-circular aperture, and a threaded 75

member for engaging a drive shaft, said threaded member having slidable engagement in said non-circular aperture.

2. In an abrasive device, the combination of a supporting pad having a hub, with an abrasive disc of relatively large size, a plurality of backing discs of different sizes adapted to be selectively used with the abrasive disc as the abrasive disc is trimmed down, and a threaded member for securing the abrasive disc and backing disc to said pad, said backing disc being constructed of laminated fiber impregnated with a phenolic condensation compound, and having a backwardly turned frusto-conical surface adjacent its outer edge whereby clogging of the abrasive is eliminated.
3. In an abrasive disc, an abrasive backing disc comprising a circular member provided with a plane body portion and a centrally located depression for receiving the head of a threaded member, said body portion carrying at its outer edge a frusto-conical backwardly turned portion for providing an increased area of contact with the work surface, said backing disc being constructed of a laminated fiber product impregnated with a phenolic condensation compound.

4. In a supporting pad for rotating abrasive discs, the combination of a pair of metallic, cup-shaped members, each having radially extending attaching flanges, and each having centrally located apertures, with a radially extending disc of metal secured to said attaching flanges by fastening devices, a hard, yet flexible, rubber disc carried by said radially extending metal disc and having integral portions extending through apertures in said metal disc, a plurality of backing members comprising laminated fiber impregnated with a phenolic condensation compound, each of said backing members being of successively larger size, and said backing members being arranged with the smallest one adjacent said rubber disc, a sheet of abrasive carried outside of the larger of said backing members, a headed metal member having its head substantially embedded in said abrasive and having a threaded portion, said headed metal member also having a non-circular outer surface engaging in a non-circular aperture in one of said cup-shaped members, the supporting pad and assembly comprising a relatively light abrasive member adapted to be rotated at a high speed for abrasive operations.

FRANS O. ALBERTSON.

25
